UNITED STATES PATENT OFFICE.

GERARD SCHUMACHER, OF ANNISTON, ALABAMA, ASSIGNOR TO UNION FOUNDRY COMPANY, OF ANNISTON, ALABAMA, A CORPORATION OF ALABAMA.

DESIGN FOR A STREET-LIGHT POST.

42,193.

Specification for Design.

Patented Feb. 20, 1912.

Application filed November 20, 1911. Serial No. 661,396. Term of patent 7 years.

To all whom it may concern:

Be it known that I, GERARD SCHUMACHER, a citizen of the United States, residing at Anniston, in the county of Calhoun and State of Alabama, have invented a new, original, and ornamental Design for Street-Light Posts, of which the following is a specification, reference being had to the accompanying drawing, forming part thereof.

The figure is a perspective view of a street light post, showing my new design.

What I claim is:—

The ornamental design for a street light post, substantially as shown.

GERARD SCHUMACHER.
